Patented Dec. 24, 1918.

UNITED STATES PATENT OFFICE.

JOSEPH E. HIXON, OF CHICAGO, ILLINOIS.

BOILER-WASHING DEVICE.

1,288,586.

Specification of Letters Patent. Patented Dec. 24, 1918.

Application filed June 21, 1917. Serial No. 176,233.

To all whom it may concern:

Be it known that I, JOSEPH E. HIXON, citizen of the United States, residing at Chicago, in the county of Cook and State of Illinois, have invented certain new and useful Improvements in Boiler-Washing Devices; and I do hereby declare the following to be a full, clear, and exact description of the invention, such as will enable others skilled in the art to which it appertains to make and use the same.

This invention relates to improvements in a boiler washing device for washing out flue boilers.

The main object of the invention is to provide a simple and efficient portable device easily inserted and operated within a flue boiler for washing the tops of the flues thereof to remove mud and scale deposited thereon.

A further object of the invention is to provide a device of the character defined which is equipped with adjustable nozzles adapted to be fixed in position to correspond to the relative elevations of the tops of horizontal series or rows of flues of the boiler so as to simultaneously wash mud and scale from the tops of the several of said rows simultaneously, and in which said nozzles are maintained always at the proper levels during travel of the device.

The invention consists in the features of construction and combinations of parts hereinafter fully described and particularly claimed.

In the accompanying drawings illustrating a suitable embodiment of the invention:

Figure —1— is a transverse section of a flue boiler showing the boiler-washing device positioned therein for washing the same.

Fig. —2— is a central longitudinal section of a washing device constructed in accordance with the invention, the same being partly broken away.

Fig. —3— is a fragmentary detail section on the line 3—3 of Fig. —2—.

Fig. —4— is a fragmentary detail section on the line 4—4 of Fig. —2—.

Fig. —5— is an end elevation of a cross-head shown at the top of Fig. —2—.

Fig. —6— is an end elevation of the discharge nozzle shown in Fig. —4—.

Referring now to said drawings: A indicates a supply pipe provided contiguous to its upper end with two diametrically op-

posed hollow arms B provided with perforations C in their outer ends, and which constitute discharge nozzles for water. Rotatably mounted on said arms B are antifriction rollers D which are confined between the pipe A and the perforated heads of said arms, the latter being annularly enlarged or flanged for this purpose. The upper end of the pipe A is closed by a perforated plug E, which also constitutes a nozzle for projecting water against the top of the boiler.

At its lower end said pipe A terminates in an elbow F to which a hose may be readily attached to connect said pipe with a source of supply of water under pressure. Between the elbow F and the cross-head, consisting of the arms B, said pipe A is provided with a plurality of longitudinal slots G. Mounted within said pipe A are short pipe sections H, which are telescopically movable therein and are longer than the slots G. Each of said pipe sections H is provided with diametrically opposed threaded openings adapted to receive the threaded shanks of discharge nozzles I. Each of the latter is provided with a plurality of perforations J disposed in the same horizontal plane and at angles to each other. The threaded shanks of said nozzles I are adapted to receive lock-nuts K of greater width than the slots G, and which are adapted to bear upon the outer wall of the pipe A at opposite sides of each of the slots G to securely clamp the pipe sections H in place. This arrangement enables the elevation or relative positions of the pairs of nozzles I to be changed and varied to accord with the distance separating the tops of the several horizontal rows of flues in the boiler from each other.

The perforations C are arranged similarly to the perforations J, as shown in Fig. —3—, so that each of the nozzles I and pipes B will project several streams of water horizontally in different directions. This arrangement causes the water jets to wash sediment and scale from the end portions of the flues contiguous to the end plates of the boiler and from the latter.

As shown in Fig. —1— the pipe A is inserted through the manhole L, the cross-head consisting of the arms B, being at this time vertically disposed. While in this position the pipe A is turned through an arc of ninety degrees and elevated until the cross-head is disposed above the elevation of the uppermost row of flues M within the boiler, and

is then turned on its own axis through an arc of ninety degrees whereupon said cross-head will rest upon the upper faces of two of said upper flues M. The nozzles I will now 5 be positioned so that the perforations J therein will be disposed in the planes of the respective rows of flues M at lower elevations. The elbow F is then connected with a hose or pipe connected with a source of 10 supply of water under high pressure, and while the water is being discharged from said nozzles and pipes B the said pipe A is moved longitudinally from end to end of the boiler while suspended from said flues. As 15 shown in said Fig. —1— the pipe A is of less length than the depth of the entire series of horizontal rows of flues M. After being disposed at the elevation shown in full lines in Fig. —1— the elbow F may be disconnected 20 from the pipe or hose and the pipe A then lowered to the position shown in dotted lines in Fig. —1—, and thereupon reconnected with the hose or pipe for continuing the washing of the flues which have not been sufficiently washed while the pipe A is positioned as shown in full lines in said figure. It is obvious, of course, that the pipe A may 25 be made of any convenient length desired.

While I have shown the preferred embodiment 30 of my invention in the accompanying drawings, it will be obvious, of course, that said embodiment may be changed and varied in details of construction without departing from the invention as defined in the appended 35 claims.

I claim as my invention:

1. A boiler washer comprising a water supply pipe, a cross-head contiguous to one

end thereof adapted to ride upon a pair of boiler flues to support said pipe, a plurality 40 of diametrically opposed pairs of discharge nozzles mounted in said pipe for directing streams of water horizontally over and upon the upper surfaces of flues disposed at different elevations below the flues from which the pipe is suspended, said cross-head provided with water discharge openings adapted 45 to discharge water over the flues upon which the washer is supported, and means for connecting said supply pipe with a source 50 of water under pressure.

2. A boiler washer including a water supply pipe adapted to be inserted between a pair of vertical rows of flues, and equipped with means for effecting connection between 55 said pipe and a source of water under pressure, a plurality of pairs of discharge nozzles carried by said pipe at various points between the ends thereof; and means for varying the relative positions of the several pairs 60 of nozzles longitudinally of said pipe.

3. A boiler washer including a water supply pipe adapted to be inserted between a pair of vertical rows of flues, and equipped with means for effecting connection between 65 said pipe and a source of water under pressure, a plurality of pairs of diametrically opposed longitudinal slots in said pipe, a plurality of pipe sections of greater length than said slots telescopically movable within said pipe for closing said slots, nozzles projecting through said slots and mounted in said pipe-sections, and means for locking said sections 70 against movement in said pipe.

JOSEPH E. HIXON.
